UNITED STATES PATENT OFFICE.

THEODORE NEWHOUSE, OF CHICAGO, ILLINOIS.

PIANO SOUND-BOARD.

SPECIFICATION forming part of Letters Patent No. 361,967, dated April 26, 1887.

Application filed February 15, 1886. Serial No. 191,930. (No model.)

To all whom it may concern:

Be it known that I, THEODORE NEWHOUSE, a citizen of the United States, residing at Chicago, in the county of Cook and State of Illinois, have invented certain new and useful Improvements in Piano Sound-Boards, of which the following is a full and complete description, when taken in connection with the drawings accompanying the specification and forming a part hereof.

My invention relates to that class of sounding-boards in stringed musical instruments where the resonant sounding-board is placed underneath the strings, by the vibration of which strings a musical tone is produced, which tone is affected by said sounding-board; and the object of my invention is, primarily, to improve the sound-board of a piano, both in the quality and quantity of the tones produced, when my invention is applied thereto. I have illustrated my invention by the drawings accompanying this specification, in which—

Figure 1 is a plan view showing the under side of a sound-board to which my invention is applied, and showing by the dotted lines the bridges on the upper side of the sound-board. Fig. 2 is a sectional elevation on line 2 2 of Fig. 1, and Fig. 3 is a sectional elevation on line 3 3 of Fig. 1.

Like letters refer to like parts throughout the several views.

A is the sound-board.

B B are the bridges.

C are ribs on the under side of the sound-board.

D D are suspension chords or ribs superimposed upon ribs C.

E E are posts or connecting-pieces placed between ribs C and suspension-ribs D. Suspension-ribs D D are of wood or like material, as are ribs C. Pieces E E are placed in position between suspension-ribs D D and ribs C and firmly glued. Ribs C are glued firmly to sounding-board A, and ribs D D are then placed upon ribs C and also glued strongly in place. Pieces E E are so placed, as indicated by Fig. 1, as to form proper and suitable supports to the sounding-board and the bridges B B placed thereon.

I am aware that sounding-boards have been 50 heretofore made having ribs C C placed on the under side thereof, and I do not therefore claim supporting, strengthening, or otherwise affecting a sounding-board by the placing thereon of ribs secured thereto, and also that 55 a double sound-board composed of two sound-boards, one in front of the back framing, the other in rear of it, said boards being sprung into an arched or crowning form by means of sound-posts introduced between them, has been 60 made; but so far as I am aware no sounding-boards have been heretofore made wherein the ribs so secured (and the sounding-board) have been supported, strengthened, or otherwise affected by the suspension-ribs and the connecting-pieces used by me.

By the use of the suspension-ribs, placed as described, I am able to reduce the amount of material used for the ribs of the sounding-board, and to obtain, in a much better manner 70 than has heretofore been done, control over the vibration of any given string strung upon or over the sounding-board.

Having thus described my invention, what I claim, and desire to secure by Letters Patent, 75 is—

1. The combination, with a sound-board for musical instruments, of the compound support consisting of the ribs C and suspension-chords D, substantially as and for the purpose 80 set forth.

2. In a sound-board, the combination of board A, ribs C, ribs D, superimposed on ribs C, and connecting-pieces E, all substantially 85 as described.

3. As an improvement in sound-boards for musical instruments, the compound support consisting of the ribs C, suspension-chords D, and posts or braces E, constructed and combined substantially as and for the purpose set 90 forth.

THEODORE NEWHOUSE.
